ABSTRACT

An electric filament or gas discharge lamp comprising a tubular glass lamp vessel which is sealed at one end by a pinch seal and has a number of filaments or electrodes supported by stiff current conductors or members. The conductors or members are passed through a common transverse support and are secured to a metal foil connection outside of the pinch seal and preferably in the space of the lamp vessel.

**ELECTRIC FILAMENT LAMP OR DISCHARGE
LAMP**

The invention relates to an electric filament lamp or gas discharge lamp which comprises a tubular glass lamp vessel which is sealed on at least one end by a pinch seal, in which vessel one or more filaments or electrodes and possibly a reflecting screen are arranged which are secured to stiff current conductors and/or supporting members passed through a common support and each secured at their one end to metal sealing foils sealed in the pinch seal, the support being secured in a few places of its circumference to the side wall of the lamp vessel. Such a lamp is described in the previously filed Dutch patent application 7,004,939.

According to the invention described in the above patent application it is proposed to secure the common support to the side wall of the lamp vessel, preferably by means of a seal. The resulting lamp is less sensitive to vibrations than a lamp in which said support, which bears on a few pole wires projecting from the pinch seal, can move.

In the above lamp a number of stiff conductors extend parallel to each other between the support and the pinch seal and they are welded to sealing foils embedded in the pinch seal.

The conductors extending between the support and the pinch seal sometimes turn out to be subject to a rather large mechanical stress which sometimes results in fracture. This may be the case, for example, when during the pinching operation the squeezing members are not moved truly perpendicularly relative to the longitudinal dimension of an elongate support. In that case a pinch seal is obtained the pinch surfaces of which can assume a slightly twisted position relative to the said support. This is also occurs when, in the case of an elongate support, the lead-in members in said support are not all of them located in the same plane.

According to the invention, this sometimes occurring drawback can be avoided by not fully embedding the foils in the pinch seal, but causing them to extend to in the lamp space, the connection place between a current conductor or supporting member and a foil being located outside the pinch seal. It has been found that by arranging the foils in this manner they can better withstand the occurring forces of deformation, due to their flexibility, than foils which are embedded entirely in the pinch seal.

In order that the invention may be readily carried into effect, one embodiment thereof will now be described briefly with reference to the drawing, in which

FIG. 1 is a longitudinal cross-sectional view of a halogen twin filament lamp, and

FIG. 2 is a cross-sectional view taken on the line II-II of FIG. 1.

Reference numeral 1 denotes a lamp vessel of quartz glass in which a support 3 having continuous stiff current conductors 5, 7 and 9 of molybdenum is sealed to the re-entrant wall parts 11 and 13 obtained by deformation. Filaments 15 and 17 of tungsten are secured to said conductors. The filament 15 is welded in addition to a reflecting screen 19 of molybdenum. Once an assembly of conductors and filaments is mounted on the support 3, it assumes, when the sealing between the support 3 and the side wall of the lamp vessel 1 is carried out, a prescribed position relative to said lamp vessel 1, which position is not changed in the pinch seal 21 to be formed subsequently.

In the lamp according to the invention, the sealing foils 23, 25 and 27 which are normally incorporated in the pinch seal 21, project in the lamp space between the support 3 and the pinch seal 21 in the manner shown, namely over such a length that the place of the weld between the conductor and the foil is likewise present in said space. It has been found that in a formed pinch seal the projecting flexible foil parts then take up a rather large force of deformation; the stresses occurring as a result of the performed pinching operation then produces a smaller reject percentage due to fracture than in the case of a foil sealed entirely in the pinch seal.

The invention may also be used in gas discharge lamps provided with a pinch seal in which a support secured to the lamp vessel does not comprise a filament but one or more electrodes. In such a gas discharge lamp, the lamp comprises a tubular glass lamp vessel which is sealed on at least one end by a pinch seal. A transverse common support is positioned within the lamp vessel and separated from the pinch seal by a lamp space. The vessel has at least one electrode of the discharge lamp being secured to a current conductor at one end thereof, the current conductor passing through the common support and being connected to a metal sealing foil at the other end thereof. The common support is secured to the side wall of the lamp vessel in at least two places of its circumference. The foil secured in the pinch seal extends into the lamp space and the place of connection between a current conductor and foil is located within the lamp space.

What is claimed is:

1. A filament lamp which comprises a tubular glass lamp vessel which is sealed on at least one end by a pinch seal, said vessel having at least one filament of said lamp secured to a current conductor at one end thereof, a transverse common support being positioned within said lamp vessel and separated from said pinch seal by a lamp space, said current conductor passing through said common support and being connected to a metal sealing foil at the other end thereof, the common support being secured to the side wall of the lamp vessel in at least two places of its circumference, wherein the foil secured in the pinch seal extends into the lamp space, the place of connection between a current conductor and a foil being located within the lamp space.

2. The electric filament lamp of claim 1 wherein said conducting member is also a supporting member.

3. The electric lamp as claimed in claim 1 wherein said filament also includes a reflecting screen.

4. A gas discharge lamp which comprises a tubular glass lamp vessel which is sealed on at least one end by a pinch seal, a transverse common support being positioned within said lamp vessel and separated from said pinch seal by a lamp space, said vessel having at least one electrode of said discharge lamp being secured to a current conductor at one end thereof, said current conductor passing through said common support and being connected to a metal sealing foil at the other end thereof, the common support being secured to the side wall of the lamp vessel in at least two places of its circumference, wherein the foil secured in the pinch seal extends into the lamp space, the place of connection between a current conductor and a foil being located within the lamp space.

5. The gas discharge lamp of claim 4 wherein said conducting member is also a supporting member.
